[57] **CLAIM**

The ornamental design for the apparatus for diluting chemical concentrates used for cleaning purposes, as shown and described.

DESCRIPTION

FIG. 1 is a perspective view of the apparatus for diluting chemical concentrates used for cleaning purposes showing our new design;

FIG. 2 is a top plan view thereof;

FIG. 3 is a front elevational view thereof;

FIG. 4 is a left side elevational view thereof, the opposite side being a mirror image;

FIG. 5 is a rear elevational view thereof; and,

FIG. 6 is a bottom plan view thereof.

The broken line drawings of conduits are for illustrative purposes only and forms no part of the claimed design.
